UNITED STATES PATENT OFFICE.

CORNELIUS G. HASTINGS, OF GLENDALE, CALIFORNIA, ASSIGNOR TO HASTINGS
TUNNEL SYSTEM COMPANY, A CORPORATION OF NEW YORK.

TUNNEL AND RETAINING WALL CONSTRUCTION.

1,240,447.

Specification of Letters Patent. Patented Sept. 18, 1917.

Application filed November 26, 1915. Serial No. 63,496.

To all whom it may concern:

Be it known that I, CORNELIUS G. HASTINGS, a citizen of the United States, and a resident of the city of Glendale, in the county of Los Angeles and State of California, have invented certain new and useful Improvements in Tunnel and Retaining Wall Constructions; and I do hereby declare that the following is a full, clear, and exact 10 description of the same, reference being had to the accompanying drawings, and to the numerals of reference marked thereon, which form a part of this specification.

This invention relates to an improved construction for retaining walls, tunnel walls, piers, and the like, and those in particular which are subjected to heavy stresses. By my invention I utilize an inner and outer retaining wall suitably laced to one another 15 by metal reinforcement members, with a filling of concrete poured or blown into the space between said inner and outer retaining walls and bonding around said members to form substantially a unitary structure 20 of great strength to withstand loads applied at any point thereon. I attain the objects of my invention by the use of building blocks of improved construction adapted to permit connection thereto of the reinforcing members between the respective inner and outer walls between which the filling 25 of concrete is placed.

It is an object therefore of this invention to provide a construction for retaining walls, 30 tunnel walls, piers and the like by building up an inner and outer wall suitably laced to one another by metallic reinforcing members, and adapted to receive a filling of concrete therebetween bonding about said members to afford substantially a unitary structure. 35

It is also an object of this invention to provide a wall construction embracing a built up inner and outer wall adapted to receive a filling of concrete or other like material therebetween, and with reinforcing members directed obliquely between the respective blocks of said walls and securely connected thereto and receiving the concrete 45 or other material bonding thereabout to hold the inner and outer walls properly disposed during the pouring of the filling ma-

terial therebetween and reinforcing the same after said material has been placed therebetween, and acting further to draw the respective blocks of the walls toward one another to insure tight joints between the assembled blocks of the respective walls. 55

It is furthermore an object of this invention to provide a wall construction involving 60 the use of an inner and outer built up wall adapted to receive a filling of concrete therebetween and with obliquely directed reinforcing members attached to the respective blocks of the respective walls and extending 65 from one wall to another to reinforce the same and receive the concrete bonded thereabout, and acting further to draw the blocks of the respective walls toward one another to afford tight joints therebetween. 70

It is also an object of this invention to provide an improved wall construction embracing inner and outer built up wall sections suitably laced together by oblique reinforcing members acting to draw the respective blocks of the walls toward one another to afford tight joints and receive a filling of concrete poured between said walls molded about said reinforcing members to afford substantially a unitary wall. 75 80

The invention (in a preferred form) is illustrated in the drawings and hereinafter more fully described.

In the drawings:

Figure 1 is a top plan view partly broken away and shown in section of a tunnel or conduit, the walls of which are constructed according to the principles of my invention.

Fig. 2 is a view taken on line 2-2 of Fig. 1. 90

Fig. 3 is a fragmentary interior elevation of the inner wall with parts broken away and parts shown in section.

Fig. 4 is a detail section with parts omitted taken on line 4-4 of Fig. 3. 95

Fig. 5 is a sectional detail view taken through portions of the outer wall portion on line 5-5 of Fig. 2.

Fig. 6 is a sectional detail illustrating the attachment of an eye clip to the T-bar form 100 associated with a row of blocks in the outer wall portion.

Fig. 7 is an elevational view of the parts shown in Fig. 6.

Fig. 8 is a vertical section taken through an upright retaining wall embodying the principles of my invention.

Fig. 9 is a fragmentary plan view thereof.

5 As shown in the drawings:

As shown in Figs. 1 and 2, my wall structure has been utilized in the construction of a tunnel or conduit wherein the outer wall portion constructed of blocks 1, laid one upon another in the usual staggered relation, is of an elliptical shape and the inner wall portion, also of a somewhat elliptical shape, is constructed of blocks 2, whereby the space 10 between said inner and outer walls is of increased width at the sides of the structure. As clearly shown in Figs. 3 and 4, the blocks 2, of the inner wall have molded therein reinforcing rods 3, which, at the inner surface of said blocks near the ends thereof, are bent 15 to extend therethrough, affording attaching eyes 4, and as clearly shown in Fig. 3, at their ends are looped to form an eye 5, whereby the respective eyes 5, of the terminating ends of said reinforcing rods, register 20 with one another to receive a retaining pin 6, inserted therethrough. At their ends each of said blocks 2, is provided with a concave semi-cylindrical recess whereby a cylindrical cavity is formed by the abutting ends of 25 said blocks into which said eyes 5, of the ends of said rods, and said retaining pins 6, are disposed, and a filling of concrete 7, is then blown therein to mold around the same.

The outer blocks 1, are laid in built up relation upon T-bar forms, the T-bars of which are denoted by the reference numerals 8, constructed and used according to the principles of my invention disclosed in my co-pending application for patent for "tunnel 30 constructions," filed July 2nd, 1913, Serial No. 776,898, and said T-bar forms are left interlocked with said blocks for use in lacing the outer wall of the structure to the inner wall by reinforcing members.

45 As shown in the detail view in Fig. 5, curved angle plates 9, are releasably connected to the T-bar forms 8, by means of bolts 10, to hold the blocks in place on the form during assembly of the blocks and thereafter hold the T-bar forms rigidly associated with the built up blocks. Attaching eyes or clips denoted by the reference numeral 11, are engaged on the flanges of the T-bar forms 8, as clearly shown in Figs. 6 and 7, and hooked or otherwise engaged therethrough are the obliquely directed reinforcement or lacing members 12, which are also engaged to the projecting eyes 4, on the blocks of the inner wall portion. Said reinforcement rods 12, are directed obliquely, not only horizontally but also vertically, thus securely holding said respective inner and outer wall portions to one another and drawing the blocks constituting the same in 50 close relation.

A filling of concrete or other material suitable for the purpose, denoted by the reference numeral 13, is then poured into the space between the retaining walls, either after a layer of the blocks constituting the 55 same has been built up, or during the progress of assembly thereof, said concrete bonding around the reinforcement members 12, and affording substantially a unitary structure, of great strength giving the desired 60 contour on the exterior of the tunnel so formed as well as on the interior thereof.

In the modification of my device illustrated in Figs. 8 and 9, I have shown my idea embodied in a straight or vertical retaining wall, wherein the outer blocks are denoted by the reference numerals 14, and the inner blocks by the reference numerals 15. As in the prior construction, reinforcement rods 16, are molded within the blocks 15, and are bent at certain points to project therethrough, affording attaching eyes 17, and similarly rods 18, are provided in the blocks 14, and bent at certain points and projecting therethrough to afford attaching 75 eyes 19. Obliquely directed reinforcement rods 20, are hooked through the respective eyes 17 and 19, to hold the wall portions associated with one another to receive a filling of concrete 21, therebetween and bonded 80 about said rods.

The operation is thought to be obvious from the description. However, it is apparent that a very substantial and practically unitary structure is afforded by the use 85 of double walls with the filling of concrete 90 therebetween and the manner of lacing the respective blocks of the opposite walls one to another.

I am aware that various details of construction may be varied through a wide range without departing from the principles of this invention, and I therefore do not purpose limiting the patent granted otherwise than necessitated by the prior art.

100 I claim as my invention:

1. In a building construction of the class described, an inner wall consisting of blocks laid in built up relation, an outer wall consisting of blocks laid in built up relation, reinforcement members molded within the blocks of said inner wall and bent to project through the surface thereof affording attaching eyes, T-bar forms supporting the blocks of said outer wall, connecting means 105 clamped on said T-bar forms, reinforcement members connected to said attaching eyes and connecting means of the blocks of said respective walls in a manner to draw the blocks of the walls toward one another to afford tight joints between the blocks, and a filling of concrete poured within the space between said inner and outer walls and bonding about said reinforcement members.

110 2. In a tunnel construction of the class 115

described, an inner built up wall, reinforcement rods molded therein and projecting through the surface thereof affording attaching eyes, an outer built up wall, T-bar forms on which the blocks of said outer wall are assembled, attaching clips engaged thereon, reinforcement members connected to said clips and to the eyes of said inner walls, and a filling of concrete between said inner and outer walls molded about said reinforcement members.

In testimony whereof I have hereunto subscribed my name in the presence of two subscribing witnesses.

CORNELIUS G. HASTINGS.
